UNITED STATES PATENT OFFICE

STEWART R. MCKAY, OF SHAKER HEIGHTS, OHIO, ASSIGNOR OF ONE-HALF TO P. E. SELBY, INCORPORATED, OF CLEVELAND, OHIO

BUILDING CONSTRUCTION

Application filed October 18, 1926. Serial No. 142,255.

This invention relates to building construction and has for one of its objects to do away with a great deal of wood, such as wood joist and studding, and to eliminate the necessity for plastering, thereby providing a construction which avoids a great deal of the disadvantage of wood, such as shrinkage and which is rendered more nearly fireproof than ordinary wood buildings, my improvements being particularly adaptable for use in construction of dwellings, garages and other buildings, which are commonly framed out of wood and are plastered on wood or metal lath.

15 A further object is to provide certain details which will enable the erection to be accomplished more rapidly than with a building ordinarily framed with wood which can be erected at a cost comparing favorably with 20 wood framed structure.

A further object is to provide a practical method or means of quickly applying and effectively securing in position gypsum board adapted to be used in place of lath and plaster 25 in the side walls, partitions and ceilings, as well as to replace the ordinary wood sheathing. By the use of this gypsum board which is manufactured and delivered ready for use in strips of predetermined width (now about 30 four feet in width) and in any length suitable for handling and applying to the structure (now up to about twelve feet in length) with my improved means for securing the gypsum board at its edges or where the joints occur 35 together with devices which I have provided for bracing the sheets of gypsum board between the joints, a very smooth surface is provided suitable for receiving directly thereon the decorations in the form of wall paper,

40 sanitos or decorating paint with either a smooth or antique surface. By these improvements eliminating the necessity for lathing and plastering there is avoided not only the most troublesome part of building construction 45 but also delays incident to the application and drying of ordinary plaster and the unfavorable effect that the moisture, which must be put in plaster, has on kiln-dried lumber, which is commonly used for the trim 50 or finish as well as doors.

The above and other objects are attained by my invention which are here briefly summarized as consisting in certain novel details of construction and combinations and arrangements of parts which will be described 55 in the specification and set forth in the appended claims.

In the accompanying sheets of drawings wherein I have illustrated the main features of my invention in the preferred form there- 60 of:

Fig. 1 is a fragmentary perspective view looking at a portion of the inside of a structure formed in accordance with my invention, parts being broken away and in section for 65 the sake of clearness.

Fig. 2 is an enlarged detail sectional view illustrating one form of that part of my invention relating to the means for securing the sheets of gypsum board.

70 Fig. 3 is a similar view showing a slight modification.

Fig. 4 is a detail sectional view to illustrate how the steel I-beam joists and studs are framed together.

75 Fig. 5 is a horizontal sectional view through a corner of the structure to illustrate how the gypsum board may be utilized and secured in place to provide the sheathing and to replace the lathing and plaster.

80 Fig. 6 is a fragmentary perspective view to illustrate how the gypsum board for the ceiling is secured to the ceiling joists and also illustrating how the strips or sheets of the gypsum board are secured together at their 85 edges or at the joints and also how they are braced between the joints to insure against sagging.

Fig. 7 is a detail perspective view illustrating particularly the manner in which the 90 partitions are formed and secured to the joists above the partitions.

Fig. 8 is a plan view of the parts shown in Fig. 7 showing the I-beam joist by dotted lines for the sake of clearness.

95 Fig. 9 is a fragmentary perspective view showing one of the braces for the gypsum board, and

100 Fig. 10 is a fragmentary perspective view to illustrate how the strips of gypsum board

forming the walls are held in true, straight condition at their upper and lower edges and illustrating how the boards forming the ceilings are joined thereto.

Fig. 11 is a view similar to Fig. 7 but omitting the I-beam joist and illustrating a modification in the construction of the support for the partition gypsum board.

In Fig. 1 I have illustrated a portion of the structure, the parts shown including a portion of the outer wall and portions of two floors which may be first and second or any pair of floors above the first. The frame work consists mainly of light steel I-beams forming the studs 10 and similar I-beams forming the joists 11. In a building to be used for a residence these studs and joists are preferably arranged approximately four feet apart. The I-beams themselves are light sections which can be handled conveniently even in the maximum lengths required. Generally for a residence the studs will extend continuously from the foundation to the upper floor joists.

For framing together the wall studs and joists and to eliminate as much as possible special fabrication of the steel, framing angles 12 are preferably provided, these extending horizontally or at right angles to the studs, adjacent the joists of each floor and being preferably secured to the studs by so-called hook bolts 13 (see particularly Fig. 4) which pass through the angles and are hooked over the flanges of the studs, these angles being used both for framing purposes and for spacing the studs, keeping them in true parallelism and in proper alignment with respect to the joists of the different floors.

At the upper ends of the studs a pair of these angles is employed as illustrated at the upper part of Fig. 1. The top floor joists are secured to these angles by means of short angle lugs 14 riveted or bolted to the joist and to the inner of the two angles 12. The outer or companion angle 12 is employed to support a wood plate to receive the roof rafters which may be formed of wood.

At the junction of the wall studs 10 with the joists of the floors beneath the topmost floor a single angle 12 is employed and is, in this instance, utilized for bracing and spacing the studs and also for another purpose to be referred to presently. The joists of these floors (which in the ordinary dwelling are the joists of the first and second floors) are preferably secured together by stampings 15, a pair of which are employed at the junction of each floor joist with the associated wall stud. These stampings have U-shaped or doubled portions formed to fit around the inside flanges of the studs and the ends of the stampings are extended outwardly in the form of flanges which are riveted or bolted to the webs of both the vertical studs and horizontal joists.

The advantages derived from the use of these stampings in framing together these floor joists with the upright wall studs is the elimination of considerable fabrication and furthermore for structures, such as dwellings and the like, I-beam sections are employed where the flanges are not sufficiently wide and have not sufficient strength to admit of the use of ordinary framing methods employed in the steel work of buildings wherein heavier sections are utilized and are required.

My invention does not contemplate the elimination of all the wood now required for dwellings and other structures of a like nature but on the other hand I propose to use both wood and steel, the structure being aptly termed a wood-steel building. Accordingly, I place directly on the floor joists 11 of the different floors wood sleepers 16 to which the wood flooring 17 is applied in the usual way. The sleepers 16 preferably consist of ordinary 2 x 4 sleepers supported edge-wise on the joists as illustrated at the lower part of Fig. 1 and they are preferably secured to the joists by wire hooks 18 which are nailed or otherwise secured to the sleepers and are hooked under the upper flanges of the joists.

Coming next to an important part of my invention it will be observed that I provide in place of the ordinary lathing and plastering and on the inner sides of the wall studs and on the under sides of the floor joists sheets of so-called gypsum board, the sheets applied to the side walls being designated 19 and the sheets applied to form the ceilings being designated 20. The width of these sheets is equal substantially to the spacing of the studs and joists, and generally one sheet will extend the full height of the wall between the floor and ceiling and usually the side walls are formed by continuous sheets extending slightly above the ceiling and slightly below the flooring 17 and in fact between the upper and lower framing angles 12. The wall sheets 19, of course, extend vertically of the studs, their side edges being at or adjacent the center lines of the studs whereas the sheets 20 of the ceilings extend crosswise or at right angles to the joists, as illustrated in Fig. 1.

Before describing how these sheets of gypsum board used for the inner walls and ceilings are held in place it might be mentioned that similar sheets of gypsum board designated 21 are provided to form the outer walls to take the place of the ordinary sheathing, these sheets being applied like the sheets 19 but to the outer faces of the studs 10.

To fill out the corners where the corner studs 10 occur (see Fig. 5) a corner angle 22 is provided, this being secured in place by suitable braces 23 which are secured to the angle 22 and to the corner studs 10 as illus-

trated in Fig. 5, and auxiliary sheets 21a constituting extensions of the outer sheets 21 extend between this angle and the outer flanges of the corner studs 10.

5 A very important feature of my invention in connection with the use of the sheets of gypsum board to form the inner and outer walls and ceilings, are sheet metal pressed or rolled securing strips which extend the 10 full length of the sheets and receive and interlock with the edges of the sheets for their full length, as well as having continuous interlocking connections with the flanges of the wall studs 10, floor studs 11 and with the 15 corner angles 22 and with angles or channels used in forming the partitions as will be explained presently.

These strips are in cross section somewhat Z-shaped in form having reversely folded 20 portions forming grooves, one to receive the edge of the gypsum board and the other to receive the edge of the I-beam or other member supporting the board. The cross sectional shape of these securing strips may be 25 varied somewhat, the precise shape depending upon the shape of the edges of the gypsum board, i. e., whether the edges are square or beveled. In Fig. 2 and in the other figures except 3, the gypsum board is shown as 30 having square edges and in these figures the securing strips are designated 24, these strips each having a groove 24a which receives, with a tight fit, the edge of the gypsum board, and, and oppositely facing groove 23b, to receive 35 the flange of the I-beam or other supporting member. It is an important feature that the securing strips tightly engage the flanges of the I-beam or other supporting member and when they are slipped onto the tapered 40 flanges, a wedging action is produced which draws the part which receives the gypsum board tight against the face of the supporting member so that the wall produced by the gypsum board is smooth and flat. Furthermore, in all instances the strips are arranged 45 back to back as clearly illustrated in Fig. 2 and other figures so as to leave no gap between the strips.

It is to be understood, however, that instead of utilizing strips extending the full 50 length of the gypsum boards I may utilize short sections placed either end to end or at intervals along the edges of the gypsum boards.

55 Preferably, the square edge sheets of gypsum board are inset slightly along their edges so that the exposed flanges of the securing strips where they fit around the edges of the gypsum board, will be slightly inset permitting the depression to be filled with prepared 60 plaster indicated at 25, so that the surface will be absolutely smooth and flush where the joints in the gypsum board occur. Throughout the major portion of the building, the securing strips for receiving the

edges of the gypsum board and for fastening them to the structural supporting members, will be of uniform shape, or cross section—in other words of stock form. But, in some places in the structure, slightly special 70 securing strips will be utilized, as for example, at the corners of the structure. These securing strips are indicated at 24c.

If the edges of the gypsum board are beveled either on a straight or curved line, the 75 securing strips will be of a form substantially as shown at 26 in Fig. 3. This will leave, between the edges a V-shaped groove adapted to be filled with prepared plaster 25 so as to leave a smooth surface the same as in Fig. 2 and permit paper, sanitos or other material to be applied to the walls thus formed, reference being had to the interior walls.

80 On the outer walls, the outer sheets of gypsum board designated 21 may be covered with any suitable material, such as shingles, stucco, ordinary siding or brick. In some instances it may be desired to omit the outer wall of gypsum board, which in Fig. 5 forms the sheet, and to form the outer wall of suitable material, such as brick placed next to the outer flanges of the I-beam studs and when this is done at regular intervals, the brick can be conveniently anchored to 85 the I-beam studs by reinforcing rods 21d embedded between the joints of the brick and hooked around the flanges of the studs. These reinforcing rods preferably extend from the flange of one stud through the brick to the flange of the adjacent stud as shown in Fig. 1.

90 The top edges of the vertical sheets of gypsum board forming the upright walls are 100 preferably received in grooved sheet metal channels to keep the edges true as indicated in Fig. 10 at 27. These channels have inwardly extending flanges 27a to receive the adjacent edges at the ends of the gypsum board sheets forming the ceiling. At the bottom of the vertical gypsum board sheets, channels, such as indicated at 28, are 105 preferably employed. The channels 27 and 28, if desired, can be secured to the top and bottom edges of the gypsum board by nails, tacks or screws.

110 As previously stated, the sheets of gypsum board at present are supplied in substantially four foot widths which corresponds to the spacing of the I-beam studs and joists. 115

I now regard it as desirable to brace both the wall and ceiling forming sheets of gypsum board with bracing members placed between the studs and joists. Between the 120 studs, these bracing members, which are 125 arranged at the back sides of the gypsum board extend vertically between the upper and lower framing channels 12. They are preferably formed of sheet metal and are 130 preferably ribbed to provide stiffness and

may be of the form indicated in Fig. 9 at 29. These are suitably secured to the framing angles 12 and are preferably provided with studs or prongs such as indicated at 29a, 5 adapted to be driven into the gypsum boards. As many of these bracing strips will be employed between adjacent studs as may be found desirable, two such bracing strips are now regarded by me as being preferred, but 10 if the gypsum board has sufficient inherent stiffness, a single bracing strip will be ample. Possibly in some instances they may be omitted altogether.

Where the ends of the gypsum board sheets 15 in the ceiling come together, I prefer to employ a bracing and securing strip such as indicated at 30 in Figs. 1 and 6. These strips are flanged and formed to provide a pair of oppositely facing grooves arranged back to 20 back as indicated in these figures to receive the edges of the gypsum board and on the back side of the gypsum board the strip is provided with a body portion suitably formed to impart the requisite stiffness, a V-shaped 25 body, being herein illustrated. The ends of these members are notched out to receive the flanges of the adjacent joists as indicated in Fig. 6.

Similar bracing strips may be employed in 30 other parts of the structure especially in some instances in partition constructions. In the ceilings it may additionally be desirable to provide between the joists bracing strips which are located at points other than at the 35 end edges of adjoining sheets where the bracing members 30 are employed as just explained. Such additional bracing strips are indicated at 31 and they may consist of angle irons which may, in some instances, be 40 formed of sheet metal, and which are suitably secured at intervals by bolts or screws to the gypsum board sheets. I contemplate securing the ends of these strips to the flanges of the joists by swinging clamps 32 which 45 are preferably bolted to the ends of the strips 31 and after the strips are applied these clamps are designed to be swung outwardly over the flanges of the joists as indicated in Figs. 1 and 6.

50 The above description has been confined chiefly to the outer walls, floors and ceilings and little mention has been made of partitions. The inner and outer sides of the partitions will, in every instance, be formed of 55 sheets of gypsum board with their edges received in the grooves of securing strips. In most instances the securing strips will be similar to those heretofore described and designated 24 and 26 and in that event they 60 will be interlocked to the flanges of upright supporting members which, in some instances, will consist of I-beam studs similar to those used in forming the outer walls and in other instances they can be conveniently 65 formed of angles or channels as indicated in

Figs. 7 and 8 where the supporting members are shown as made up of two pairs of angles 33, which at their upper and lower ends will be fastened by angle plates 34 to the flanges of the joists above and beneath. Hook bolts 70 similar to the hook bolts 13 shown in Fig. 4 will be preferably employed to secure the angle plates to the flanges of the I-beam studs.

In this instance, the outer flanges of the 75 pairs of angles take the place of the flanges of the I-beam studs of the outer walls and floors and the securing strips, such as strips 24, will receive the adjacent edges of the sheets of gypsum board here designated at 35 and will fasten them to the flanges of the angles the 80 same as to the studs.

Instead of using either I-beam studs or angles as in Figs. 7 and 8, to form the upright 85 securing members to which the gypsum board sheets of the partitions are secured, these members may consist of special sheet metal channels arranged in pairs as shown at 36 in Fig. 11, in which event they will be provided at their edges with flanges forming grooves 36a to receive the adjacent upright edges of the partition forming gypsum board. At 90 their upper ends, these channels may be fastened to the upper and lower I-beam joists by angle plates 34 similar to those indicated in Figs. 7 and 8.

95 With the construction above described all the advantages enumerated in the early part of this specification are obtained very effectively.

100 It is to be noted that while in the ordinary wooden building the joist and stud are arranged on about 16 inch centers, I arrange the light I-beam studs and joists on approximately 4 foot centers and by the use of the intervening bracing and stiffening members, such as the vertical bracing and stiffening members 29 between the studs and the horizontal bracing and stiffening members 31; between the joists, the effect of a wood frame 105 with 16 inch centers is obtained with a minimum amount of steel.

110 I do not wish to be confined to the precise arrangements and details shown herein, but aim in my claims to cover all modifications 115 which do not depart from the spirit and scope of my invention.

Having thus described my invention, what I claim is:

120 1. In a building construction, a frame having flanged steel frame members, wall forming gypsum board adapted to form the inner or outer wall surfaces, and sheet metal strips for securing the same with their edges adjacent each other to the steel frame members and having grooved portions receiving the 125 edges of the gypsum board and other grooved portions fitted onto the flanges of the steel frame members whereby each gypsum board is individually secured against the inner or outer face of the frame members.

2. In a building construction, horizontal and vertical steel frame members, sheets of gypsum board for forming upright and ceiling walls, and sheet metal securing strips having grooves which receive the edges of the gypsum board and additional grooves which receive the flanges of the steel frame members whereby each gypsum board is individually secured against the inner or outer 10 face of the frame members.

3. In a building construction, horizontal and vertical steel frame members, sheets of gypsum board for forming upright and ceiling walls, and sheet metal securing strips having grooved portions which receive the edges of the gypsum board and additional grooved portions which receive the flanges of the steel frame members, the last mentioned grooved portions fitting onto the 20 flanges of the frame members with a wedge action so as to draw the first named grooved portions tightly against the faces of the frame members whereby each gypsum board is individually secured against the inner or outer 25 face of the frame members.

4. In a building construction, flanged steel frame members arranged on predetermined centers, sheets of gypsum board forming the inner or outer walls and having their edges at substantially the centers of adjoining frame members with the edges of the adjoining sheets close to each other so as to form a substantially unbroken surface, and pairs of sheet metal securing members having grooved 30 portions arranged back to back and receiving the adjoining edges of the gypsum board sheets and having other grooved portions separately fitted around the flanges of the frame members whereby each gypsum board 35 is individually secured against the inner or outer face of the frame members.

5. In a building construction, flanged steel frame members arranged on predetermined centers, sheets of gypsum board forming the inner or outer walls and having their edges at substantially the centers of adjoining frame members with the edges of the adjoining sheets close to each other so as to form a substantially continuous surface, and pairs 40 of sheet metal securing members having grooved portions arranged back to back and receiving the edges of adjoining gypsum board sheets and having other grooved portions separately fitted around the flanges of 45 the frame members, and bracing members lying between adjacent frame members and engaging the sheets of gypsum board between their edges.

6. In a building construction, vertical and horizontal flanged steel frame members, means including upper and lower angles for framing said members together, sheets of gypsum board secured to said frame members to form a substantially unbroken 50 surface, and bracing members for the sheets of

gypsum board arranged between the frame members and secured at their ends to said angle iron framing members.

7. In a building construction, flanged steel vertical and horizontal frame members, 70 means including upper and lower angles for framing said members together, sheets of gypsum board secured to the faces of said frame members and arranged so as to form a substantially unbroken wall surface, and 75 bracing members arranged between the frame members and at their ends secured to the angle framing members and between their ends being secured to the sheets of gypsum 80 board.

8. In a building construction, vertical and horizontal flanged steel frame members secured together, means comprising sheet metal members receiving the edges of the sheets of gypsum board and the flanges of the frame 85 members so as to secure the gypsum board to the frame members with their longitudinal edges adjacent the centers of the frame members, and sheet metal bracing and securing members receiving the adjacent end edges 90 of the adjoining sheets and extending between certain of said frame members whereby each gypsum board is individually secured against the inner or outer face of the frame 95 members.

9. In a building construction, vertical and horizontal flanged steel frame members arranged upon predetermined centers and framed together, sheets of gypsum board secured at their edges to the faces of said 100 frame members with their longitudinal edges coinciding substantially with the centers of the frame members, upright bracing members arranged between the vertical frame members and secured to the vertical sheets 105 of gypsum board, and transverse bracing members extending between the horizontal frame members and secured to the horizontal sheets of gypsum board.

10. In a building construction, vertical and horizontal flanged steel frame members, the horizontal members being arranged to form different floors of the building, and means comprising stampings fitted around the flanges of the vertical frame members for 110 securing the latter to the horizontal frame members of one floor.

11. In a building construction, vertical and horizontal flanged steel frame members, the horizontal members being arranged to form 115 different floors of the building, means comprising stampings fitted around the flanges of the vertical frame members for securing the latter to the horizontal frame members of one floor, and means comprising angle 120 irons for spacing the vertical frame members, certain of said angle irons serving as framing members to secure the vertical frame members to the horizontal frame members of another floor.

12. A building of the wood-steel type comprising vertical and horizontal flanged steel frame members framed together with the horizontal frame members arranged for different floors, gypsum board secured to the faces of the vertical and horizontal frame members to form substantially unbroken walls, wood sleepers extending across and resting upon the horizontal frame members of one or more floors and wood flooring secured to said sleepers. 5
13. In a building construction, a frame comprising flanged steel frame members, sheets of gypsum board for forming upright and ceiling walls, said sheets having their abutting edges reduced in thickness, and means cooperating with the reduced edges and engaging the flanges of the frame members for securing the sheets thereto. 15
14. In a building construction, a frame comprising flanged steel frame members, sheets of gypsum board for forming upright and ceiling walls, said sheets having their abutting edges reduced in thickness, and 20 sheet metal securing strips cooperating with the reduced edges and engaging the flanges of the frame members for securing the sheets thereto, whereby each gypsum board is individually secured against the inner or outer face of the frame members. 25
15. In a building construction, a frame comprising flanged steel frame members, sheets of gypsum board for forming upright and ceiling walls, said sheets having their abutting edges reduced in thickness, and sheet metal securing strips having grooves which receive the reduced edges of the gypsum board, and additional grooves which receive the flanges of the steel frame members. 30
16. In a building construction, a frame comprising flanged steel frame members, sheets of gypsum board for forming upright and ceiling walls, said sheets having depressed portions along their abutting edges, sheet metal securing strips having grooves which engage the depressed portion of the boards below the surface thereof, and additional grooves which engage the flanges of the steel frame members, and a filler in said depressed portions whereby a smooth, unbroken wall surface is produced. 35
17. In a building construction, a frame comprising flanged steel frame members, sheets of gypsum board for forming upright and ceiling walls, said sheets having depressions along their meeting edges, means secured in the depressions for securing the boards to the frame members, and a filler in said depressions whereby a smooth, unbroken surface is produced. 40
18. In a building construction, a frame comprising flanged steel frame members, sheets of gypsum board for forming the walls, and means for securing the sheets to the frame members, comprising sheet metal 45

members bent to substantially S-shape thereby forming oppositely disposed grooves which receive the edges of the gypsum board and the flanges of the frame members. 50

19. In a building construction, a frame comprising flanged steel frame members, sheets of gypsum board for forming the walls, and means cooperating with the edges of the boards and engaging the flanges of the frame members for securing the boards to the latter. 75

20. A building of the wood-steel type, comprising vertical and horizontal flanged steel frame members framed together with the horizontal members arranged for different floors, sheets of gypsum board secured to the flanges of the vertical and horizontal frame members to form substantially unbroken walls, wood sleepers extending across and resting upon the horizontal frame members of one or more floors, and wood flooring secured to said sleepers. 80

In testimony whereof, I hereunto affix my signature.
